UNITED STATES PATENT OFFICE

NICOLAS EMILIEN METHLIN, OF PARIS, FRANCE, ASSIGNOR TO SCHNEIDER & CIE,
OF PARIS, FRANCE, A LIMITED JOINT-STOCK COMPANY OF FRANCE

COMBINED PROJECTILE AND BREECH BLOCK FOR ORDNANCE

Application filed March 26, 1928, Serial No. 264,769, and in France April 14, 1927.

The object of the present invention is to provide a particular mode of construction of the movable breech block or of the fixed obturator of a piece of ordnance and of the projectile which is to be fired with the latter.

5 It has already been proposed, in particular for trench mortars or other short range guns, to provide the projectile with a rear extension suitably guided in a diaphragm 10 formed in front of the chamber partly occupied by the ejecting charge. In these known devices in which it was proposed to exert the action of the gases of the charge upon only a small surface at the commencement of the movement of the projectile, the charge only occupied a very small part of the space in which combustion took place. As a consequence, the gases produced by the combustion, before acting upon the projectile, 15 had to pass through an expansion chamber of large volume, and the action of the gases upon the small surface of the projectile was effected with a very rapidly increasing volume, and consequently a very rapidly decreasing pressure.

20 It has also been proposed to confine the charge in a small chamber, the volume of which remains practically constant at the commencement of the ejection of the projectile, this chamber being closed by a diaphragm in which engages a central extension member projecting from the base of the projectile.

25 This last solution, which is by far the better from the point of view of the result to be obtained, presents however, the disadvantage of requiring the use of projectiles comprising an axial rearwardly extending member of small diameter and difficult to store and 30 handle.

The invention removes the disadvantages of both the known systems described above.

35 The subject of the invention is a breech block or obturator and a projectile combined 40 in such a way that the combustion of the gases can take place practically in a closed space, the pressure of which gases can increase rapidly and preserve a high value for a suitable length of time.

45 50 According to the invention the projectile

and the obturator comprise, one a male part and the other a female part or vice versa, arranged so as to engage fairly accurately one in the other for firing, and these interengaging male and female parts are characterized by the feature that, when in the position of engagement, they bound a closed chamber in which is confined the ejecting charge.

55 The invention may advantageously be employed in combination with mortars or other like guns comprising in the neighbourhood of the chamber which contains the ejecting charge, one or more orifices, the section of which may be regulated if desired, for the escape of a part of the gases produced by the combustion of the charge.

60 Of the mutually engaging male and female parts which enclose, at the moment of firing, the closed chamber in which is contained the ejecting charge, one may be formed upon the base of the projectile and the other upon a solid and fixed obturator, in the case of muzzle loading guns. They may, in the case of breech loading guns, comprising a breech 65 opened and closed by hand or automatically, be mounted one upon the base of the projectile and the other upon a movable head bearing upon a plastic or elastic obturator.

70 Various forms of construction of the invention are illustrated by way of example in the accompanying drawing.

75 Figs. 1 and 2 show in longitudinal sectional elevation two different positions of a first form of the invention applied to a muzzle loading mortar comprising a discharge duct 80 for the gases produced by the combustion of the charge.

85 Fig. 3 is a plan section taken along the line 3—3 in Fig. 1.

90 Fig. 4 shows in longitudinal sectional elevation another embodiment of the invention.

95 Figs. 5, 6 and 7 respectively illustrate further embodiments of the invention as applied to a breech loading gun having a movable breech block.

100 In these figures 1 to 3, inclusive, A is the barrel of the gun, closed at the rear end by a solid obturator B. C is the projectile.

In this first example, the male part is formed by a central projection or boss D on

the obturator B. At the centre of this boss 5 may be formed a striker E. The striker may also be movable in an axial duct in the obturator and be adapted to be operated by hand or by any other known firing device.

The female part adapted to engage upon 10 the male part D is formed in the base C¹ of the projectile. It may be formed by a sleeve F which will engage upon the part D over a suitable portion f of its height, while it will define, with the base of the projectile, the chamber intended to contain the ejecting charge G. At the centre of a 15 diaphragm F¹, suitably perforated with holes f¹, is secured a primer H.

The firing mechanism may be so arranged 20 that it will operate automatically when the projectile, loaded through the muzzle, is placed in position and at the moment when the engagement of F upon D has been completely effected.

As will be seen in the drawing, the parts 25 F and D form, by their combination with the boss of the projectile, a completely closed chamber, in which the ejecting charge is confined when the projectile is placed in position for firing.

Combustion, at the commencement of 30 ejection, thus takes place in a practically closed chamber. The pressure, which develops very rapidly, is wholly exerted upon the small face of the boss D of the obturator and reaches a high value at the commencement of ejection and until the moment when the projectile has passed beyond the position indicated in Fig. 2. At this moment the gases will be free to expand around the completely disengaged boss D and escape in part 35 through the orifice I. In this way an excellent and complete combustion of the ejecting charge is secured and the desired range is obtained with certainty.

Fig. 4 shows in longitudinal sectional elevation an embodiment of the invention adapted for use, as in the preceding example, in a muzzle loading gun. In this case the female part F is formed upon a fixed obturator B and the striker E may move on, or be formed as a projection upon its inner end. The male part D is formed by a sleeve screwed into the base of the projectile C and containing the ejecting charge G. The charge containing chamber has arranged 45 along its axis, a primer H for automatic or other firing when the engagement between the male and female parts is completed, and the cup or female part F formed in the obturator may comprise a fixed striker E projecting from its centre, or guiding ducts for a striker adapted to be operated by hand or by any other suitable means.

As in the preceding example, combustion 50 takes place on the back face of the charge G; it takes place in a closed chamber, and

a pressure is exerted upon a small section of the obturator B.

Figs. 5, 6 and 7 show examples of the invention applied to a breech loading gun comprising an elastic or plastic obturator with 70 a movable head, the breech block being alternately opened for the insertion of the projectile and closed for firing.

In the example shown in Fig. 5 the female part is formed by a sleeve F screwed into the 75 base of the projectile C behind the chamber provided in the said base for the ejecting charge G. The male part D is formed on an axial head K bearing upon an elastic obturator J and movable in a breech block B opened and closed by hand or automatically.

As in the preceding examples, the projectile comprises no axially extending member of small diameter projecting from its base; the engagement is obtained by simply 80 sliding the base of the projectile over the movable head D of the breech block or by the engagement of concentric projections D and D¹ on this head in corresponding lodgments in the sleeve F screwed into the base. 85 In this last case, the central part D¹ of small diameter alone receives, at the commencement, the direct action of the gases from the primer H passing through an axial duct in the movable head.

Fig. 6 shows an embodiment in which the female part F is formed by a recess in the movable head K of the breech block B. The male part D is formed by the base of the projectile itself, containing the charge G and closed by an end piece perforated with holes.

Fig. 7 shows an embodiment in which the female part F is formed in the base of the projectile, the male part being formed by an annular projection D on the movable head, 105 and forming with the latter a chamber for holding the charge G.

Claims:

1. In combination, a gun, a projectile therefor having a substantially cylindrical base portion fitting the bore of said gun, cooperating telescoping means forming parts respectively of the closed end of said gun and of said cylindrical base portion, said means having a diameter substantially less than said cylindrical base portion and defining a closed combustion chamber, and a propelling charge in said chamber.

2. In combination, a gun, a projectile therefor having a substantially cylindrical base portion fitting the bore of said gun, a recess formed in the base of said projectile, means forming a part of the closed end of said gun and having telescoping engagement with the walls of said recess to define a combustion chamber, and a propelling charge in said chamber.

3. In combination, a gun barrel, a projectile therefor having a substantially cylindrical base portion fitting the bore of said barrel,

- 5 said projectile having a recess in its base, the central portion of the closed end of said gun barrel being shaped to have telescopic engagement with the walls of said recess to define a combustion chamber having a diameter substantially less than the diameter of said base, and a propelling charge in said chamber.
- 10 4. In combination, a gun barrel, a projectile therefor having a substantially cylindrical base portion fitting the bore of said barrel, cooperating telescoping means forming parts respectively of the closed end of said gun and of said cylindrical base portion, said means defining a combustion chamber having a diameter substantially less than the base of said projectile, and a propelling charge in said chamber, said gun barrel having an opening in its wall adjacent the combustion chamber for the escape of gasses of combustion. 75
- 15 5. In combination, a gun barrel, a projectile therefor having a substantially cylindrical base portion fitting the bore of said barrel, said projectile having a recess in its base, the closed end of said gun having a boss fitting within said recess to define a closed combustion chamber, said barrel having an opening in its wall adjacent the combustion chamber for the escape of gases of combustion, and a 90 propelling charge in said chamber. 95
- 20 6. In combination, a gun barrel, a projectile therefor having a substantially cylindrical base portion fitting the bore of said barrel, said projectile having a recess in its base, a propelling charge in said recess, and means forming a part of the closed end of said gun barrel and having telescopic engagement with the walls of said recess to define a combustion chamber, said gun having an opening in its wall adjacent the combustion chamber for the escape of gases of combustion. 100 105
- 25 7. In combination, a gun barrel, a projectile therefor having a substantially cylindrical base portion fitting the bore of said barrel, said projectile having a recess in its base, the central portion of the closed end of said gun barrel being shaped to have telescopic engagement with the walls of said recess to define a combustion chamber having a diameter substantially less than the diameter of said base, and a propelling charge in said recess. 110 115
- 30 8. In combination, a gun barrel, a projectile therefor having a substantially cylindrical base portion fitting the bore of said barrel, said projectile having a recess in its base, a boss in the closed end of said gun barrel positioned centrally of the bore thereof and fitting within said recess to define a closed combustion chamber having a diameter substantially less than said base, and a propelling charge in said chamber. 120 125
- 35 9. In combination, a gun having a breech block, a projectile for said gun, said projectile having a recess formed in its base, a pro- 130
